Primary Examiner — Angela J Lee(74) Attorney, Agent, or Firm — Michael J. Striker(57) CLAIM

I claim the ornamental design for a tablet holder, as shown and described.

DESCRIPTION

FIG. 1 is a front 3/4 perspective view of a tablet holder showing my new design;

FIG. 2 is a rear 3/4 perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof; and,

FIG. 9 is a front 3/4 perspective view showing the tablet holder in use.
